MACHINE AND METHOD FOR FORMING
WATCH CRYSTALS

Albert Small, New York, N. Y., assignor to Snapfit
Round Crystal Corporation, New York, N. Y., a
corporation of New York

Application January 24, 1935, Serial No. 3,365

3 Claims. (Cl. 33—28)

My invention relates to a new and improved machine and method for cutting watch crystals.

One of the objects of my invention is to provide a machine and method for making said crystals from a sheet of flexible and transparent material, such as "celluloid", cellulose acetate and the like.

Another object of my invention is to provide a machine and method whereby said crystals can be cut to proper oversize from a sheet of flat and transparent material.

Another object of my invention is to provide a simple machine which can be conveniently used in order to cut the crystal to proper oversize corresponding to the size of the bezel in which the crystal is to be inserted.

Other objects of my invention will be set forth in the following description and drawings which illustrate a preferred embodiment thereof, it being understood that the above statements of the objects of my invention are intended to generally explain the same without limiting it in any manner.

Fig. 1 is a top plan view of the improved machine.

Fig. 2 is a front elevation of Fig. 1, being taken on the line 2—2 of Fig. 1.

Fig. 3 is a view on the line 3—3 of Fig. 1.

Fig. 4 is a view similar to Fig. 3, showing the scoring or cutting member and the score or cut which has been formed by said member.

Fig. 5 is a sectional view of the blank after it has been scored or cut.

Fig. 6 is a side elevation of the completed crystal, in planar form.

Fig. 7 is an enlarged top plan view, showing the mechanism for regulating the position of the scoring or cutting member. Fig. 7 also shows how the cutting or scoring member is first adjusted, in accordance with the size of the bezel in which the crystal is to be inserted.

Fig. 8 is a view similar to Fig. 7, showing the bezel removed, and also showing the final adjustment of the cutting or scoring member, in order to cut an oversize bezel from the blank.

Fig. 9 is a sectional view on the line 9—9 of Fig. 1.

Fig. 10 is a sectional view on the line 10—10 of Fig. 9.

Fig. 11 is a detail bottom plan view showing a portion of the device.

The machine is provided with a base 1, having a standard 2 at one end thereof, and having a second standard 3 at one side thereof. The base 1 and the standards 2 and 3 can be made of a

single casting. For convenience it may be stated that the standard 2 is at the front of the device. The standard 3 is intermediate the front and rear ends of the base 1. A swivel member 4 is turnably mounted in the standard 2, so that the swivel member 4 can be turned around a vertical axis. The swivel member 4 has a flange 4a which slidably abuts the top of the standard 2.

As shown in Fig. 9, the swivel member 4 is also provided with a neck 5, which fits turnably and closely in a corresponding bore which is provided in the standard 2.

As shown in Fig. 9, the base 1 is provided with a depending flange 7 at its bottom.

A stop plate 8 is connected to the neck 5 by 15 means of a screw 9 or any other suitable fastening means. The plate 8 turns in unison with the swivel member 4. The stop plate 8 may be additionally connected to the neck 5, by means of pins 10.

The plate 8 can be forced out of contact with the pins 10, by using any suitable tool, if it is necessary to take the device apart.

The pins 10 have a drive fit in recesses which are provided in the neck 5. The bottom surface 25 of the base is provided with a stop pin 11, and the rim of the stop plate 8 is provided with a cut-out portion having the edge 12, so that the pin 11 operates to limit the turning movement of the swivel 4, when said swivel 4 is turned so that the 30 parts are in the position shown in Fig. 1.

The stop pin 11 may also limit the turning movement of the swivel 4, away from said position shown in Fig. 1, although this ordinarily is limited by other stop means which will be later 35 described.

The swivel member 4 is cast integral with a lateral bearing member 14, which is open at a part of its top.

The top surface of the lateral member 14 is 40 generally planar, save for the upwardly curved portion 15 thereof. The member 14 is hollow, and a part of its top surface is provided with a slot 16. Another part of said top surface is provided with a slot or opening 17, which is wider 45 than the slot 16.

An adjusting screw 18 is located within the lateral member 14. Said screw 18 has a pin P connected therewith, and said pin projects through the slot 16. Said pin P prevents the turning of the screw 18, so that, when said screw 18 is acted upon by a suitable nut member, said screw 18 is moved back and forth within the bore 22 of the lateral member 14, together with the pin P.

The inner wall of said bore 22 is smooth, and the screw 18 fits snugly but slidably within said bore 22, which serves as a guide for the axial movement of the screw 18. The screw 18 is 5 moved back and forth within the bore 22 by means of a hollow nut member 20, having a reduced end portion 21, whose inner wall is internally threaded.

Hence when the nut member 20 is turned about 10 its own axis the screw 18 is moved back and forth together with the pin P.

The nut member 20 has an externally threaded portion 20a, which fits within a corresponding bore of the transverse member 14. The externally threaded part 20a is spaced from the internal wall of the adjacent part of the bore of the transverse member 14. The externally threaded member 20a passes through the internally threaded bore of a follower 30. A cutting 15 or scoring tool 31 is adjustably clamped to the follower 30 by means of a set screw 32.

As shown in Figs. 7 and 8, the cutting member 31 has a cutting or scoring end 31a which may be of any suitable shape. In the preferred form of 20 the device, said cutting or scoring end 31a has a planar top face, as shown in Fig. 10, and the bottom of said cutting tool is of a general rounded or convex contour. The top surface of said cutting or scoring point 31a, has two straight 25 edges which are inclined to each other at an angle of about 45°.

I do not wish to be limited to any particular shape for the cutting or scoring point.

A bearing nut 33 is provided with a neck 33a 30 which is externally threaded. The external threading 33a cooperates with internal threading which is located at the inner surface of the end wall 19, so that the nut 33 is held firmly in position relative to said end wall 19.

The member 20 has a reduced neck 20b, 35 which extends through the internal bore of the nut member 33. Hence, the member 33 serves as a bearing for the member 20, and an additional bearing is provided by the reduced end 21.

A cap 34 is connected to the external neck 20b, 40 by means of a removable pin 35. The operating cap 34 is provided with a flange 34a having longitudinal markings 34b. The nut member 33 is provided with a single index marking 38, which 45 cooperates with the index markings 34b on the cap 34.

When the cap 34 is turned, the nut member 20 is turned in unison therewith, thus causing 50 the pin P and the cutting tool 31 to be moved back and forth in unison.

The pitch of the screw 18 is coarser than the pitch of the thread of the member 20a, so that the pin P is moved through a distance which is twice as great as the distance through which the 55 cutting tool is moved.

The standard 3 is provided with a bearing in which a shaft 40 is located. Said shaft 40 is integral with a head 41, which is external to the bore or bearing in which the shaft 40 is located. 60 The head 41 is of greater diameter than the shaft 40. The head 41 is also integral with a disc 42.

The operating handle 43 is provided with a head 43a and said head has an internally-threaded bore so that it can be screwed on the externally threaded end 40a of the shaft 40. The 65 end portion 40a is of smaller diameter than the shaft 40.

A coil spring 44 is located partially within a recess which is provided in the outer end of the 70 sleeve bearing 45, in which the shaft 40 is located.

Said coil spring 44 is also partially located within a recess of the head 43a. When the head 43a is screwed into position, it compresses the spring 44 and the inner face of the head 43a is slightly spaced from the adjacent edge of the bearing 5 sleeve, in order to eliminate friction and to permit free turning of the shaft 40.

A nut 46 holds the head 43a assembled with the threaded member 40a. The spring 44 holds the head 43a in the slightly spaced relation relative to the adjacent face of the sleeve 45, in order to prevent binding. The disc 42 is provided with a plurality of holding members 50, which are turnably connected to said disc 42 by means of screws 51. Each said screw 51 is provided with a thumb-nut 52, so that each said holding member 50 can be clamped into proper adjusted position.

A planar blank B made of the material which is to be cut or scored, is held to one planar face of the disc 42, by means of the holding members 20 50, which partially overlap said blank B. The turnable holding members 50 make it possible to clamp blanks B of many different sizes to the face of the disc 42.

In order to use the device, the swivel 4 is turned 25 until the parts occupy the position shown in Fig. 1. The watch-bezel W is then located upon the planar face at the top of the transverse member 14. This face has a fixed pin Pa.

The watch bezel is placed so that the pin Pa 30 abuts a part of the inner rim of said watch bezel. The watch bezel is inverted when it is placed upon the planar face of the member 14, as shown in Fig. 7.

I have shown a conventional type of watch bezel 35 W which ordinarily has its inner rim recessed, as shown at 53.

The cap 34 is then turned so as to actuate the pin P, until it snugly abuts the inner periphery of the watch bezel W, as shown in Fig. 7.

The distance between the fixed pin Pa, and the adjustable pin P should then correspond more or less accurately to the diameter of the seat into which the crystal is to be inserted. An experienced operator can do this with considerable accuracy. 45

After this preliminary adjustment, the watch bezel W is removed, and the cap 34 is then turned so as to increase the distance between the fixed pin Pa and the movable pin P. The extent of this additional turning can be determined by the scales which are provided by the index marking 38 and the scale markings 34b. The increase of the distance between the pins can be readily determined by an experienced operator and this depends upon the amount of doming of the crystal when the same is inserted into the bezel. 55

This adjustment also moves the cutter 31 to the proper position.

The swivel member 4 is then turned approximately 90° until the cutter is in the dotted line position shown in Fig. 2.

The transverse member 14 is provided with a depending arm 60, and this cooperates with a plurality of superposed stop members 61 which are connected to an upright lug 62 which is integral with the base 1. These stop members 61 may be adjustable and they may consist of screws or the like which can be threaded into internally threaded bores of the lug 62. Said stop members 61 are preferably provided with nuts 61a in order to hold said threaded stop members 61 tightly in adjusted position.

The depending arm 60 thus abuts the ends of 75

the stop members 61, which project beyond the nuts 61a.

When the tool 31 is in the position shown in dotted lines in Fig. 2, its point 31a is pressed 5 against the blank B.

The handle 43 is now operated to turn the disc 42, together with the blank B which is clamped firmly on the disc 42. The tool 31 thus forms a 10 circular score line C, in the blank B. While this is being done the operator presses the handle 60 towards the stop members 61, with suitable force, so that the circular score line C is formed gradually while the disc 42 is turned a suitable number of revolutions. The tool does not cut through 15 the blank B.

After the scoring operation has been completed to a suitable depth, the blank B is removed from the disc 42 and upon exerting suitable pressure the finished crystal 70 is separated from the 20 blank B. The score line C extends almost completely through the blank B but the point 31a of the tool does not contact with the smooth planar surface of the disc 42.

As shown in Fig. 6, the crystal 70 has a tapered edge. This crystal is now inserted into the groove of the bezel and since the crystal is oversized, it is sprung into dome-shape as it is inserted. For this purpose I use well known tools which flex the crystals 70 temporarily into dome 30 shape, as the crystal is inserted into the bezel. When these tools are removed, the resilience of the bezel retains it in said dome shape and firmly seated in the seat of the bezel W.

As shown in Fig. 10, the member 30 may be 35 provided with a slit 80 at its bottom, and with additional slits 81. These slits give suitable resilience to the corresponding part of the nut member 30. If desired, the depending shank of the nut member 30, having said slits, may have 40 some frictional fit within the transverse member 14, in order to hold the member 30 in its adjusted position.

As shown in Fig. 10, the member 30 is provided with shoulders which slide upon the top edges 45 of the member 14.

It will be noted that the adjustment of the pin P corresponds to the full diameter of the seat of the bezel and that the adjustment of the cutting tool corresponds to a radius or to one-half of 50 said diameter. For this reason the threads of the members 28a and 18 have their pitch in suitable relation for securing these differential movements.

For convenience the pin P may be designated 55 as a "gauge" pin. In the specific embodiment illustrated, the gauge pin and the cutter are simultaneously adjusted by the same means. However, the invention is not necessarily limited to this specific embodiment as I claim that it is 60 novel to provide means whereby the adjustment of the cutting or scoring tool is controlled by the adjustment of the gauge pin.

I have shown a preferred embodiment of my 65 invention, but it is clear that numerous changes and omissions can be made without departing from its spirit.

I claim:

1. A machine for forming a watch crystal comprising a blank-support and means for turning

said support, said blank-support having means for clamping a blank of material thereon, a second supporting member which is turnably mounted relative to said blank-support, said second supporting member being adapted to support a bezel thereon, said second supporting member having gauge means which include an adjustable gauge pin, said second supporting member also having a tool which is located on an adjustable mount, said second supporting member also having means for actuating said mount and said adjustable gauge pin simultaneously, the point of said tool being exposed relative to said second support, so that said point can be forced against the blank which is held on 15 said blank-support when the second supporting member is turned into proper position.

2. A machine for forming watch crystals comprising a base, a turnable disc mounted on said base, said disc having clamping means for clamping a blank thereto, a swivelled member turnably mounted on said base, said swivelled member having a longitudinal slot and a movable pin which projects through said slot, said swivelled member also having a fixed pin which is mounted on the same face thereof as said slot, a screw mounted within said swivelled member and having said movable pin connected thereto, a nut-member located within said swivelled member, said nut-member having an internally threaded 25 portion which cooperates with the thread of said screw so that the screw is moved back and forth when the nut-member is turned, means for actuating said nut-member, said nut-member having an externally threaded portion, a follower 30 mounted on said externally threaded portion, and a tool connected to said follower and projecting beyond said swivelled member, the pitch of the externally threaded portion of the nut-member being half the pitch of said screw, said 35 swivelled member being so positioned that it may be turned toward said turnable disc and bring the tool into engagement with the blank secured to said disc, the machine having stop means for limiting the turning movement of the swiv- 45 elled member towards said turnable disc.

3. A machine for forming a watch crystal, said machine comprising a base, a blank-support turnably mounted on said base, a second supporting member which is turnably mounted on 50 said base, said second supporting member being turnable around an axis which is perpendicular to the axis of said blank-support, said second supporting member being adapted to support a bezel thereon, said second supporting member 55 also having gauge means which include an adjustable gauge pin, said second supporting member also having a tool which is located on an adjustable mount, said second supporting member also having means for simultaneously actuating said mount and said adjustable gauge pin at a predetermined ratio of movement, the point of said tool being exposed relative to said second support, so that said point can be forced against the blank which is held on said blank-support 60 when the second supporting member is turned into proper position.

ALBERT SMALL.
